UNITED STATES PATENT OFFICE

JAMES G. GREENE, OF ELIZABETH, NEW JERSEY, ASSIGNOR TO THE SINGER
MANUFACTURING COMPANY OF NEW JERSEY.

CLAMP FOR BUTTON-HOLE SEWING-MACHINES.

SPECIFICATION forming part of Letters Patent No. 339,640, dated April 13, 1886.

Application filed December 3, 1885. Serial No. 184,542. (No model.)

To all whom it may concern:

Be it known that I, JAMES G. GREENE, a citizen of the United States, residing at Elizabeth, in the county of Union and State of New Jersey, have invented certain new and useful Improvements in Clamps for Button-Hole Sewing-Machines, of which the following is a specification, reference being had therein to the accompanying drawings.

10 My invention relates to that class of work-clamps adapted to open and spread the button-hole after the work has been clamped, and it comprises certain improvements on the clamp shown by my Patent No. 319,700, dated June 9, 1885, the object of the present invention being 15 to render my clamp more convenient for use.

In the drawings, Figure 1 is a plan view of a clamp embodying my invention, and Fig. 2 is a cross-section of the same on the line 2 2, 20 Fig. 1. Fig. 3 is a plan view with the upper clamping-jaws removed; Fig. 4, a partial plan view showing the lower jaws spread apart. Fig. 5 is a side elevation of the clamp with the parts in the same positions as in Figs. 1, and 25 with the spreading-lever in section. Fig. 6 is a detail view of the spreading-lever, and Fig. 7 a longitudinal section of the clamp.

A denotes the base-plate of the clamp, and BB the lower clamping plates or jaws, adapted 30 to slide laterally on the base-plate, the lateral movements of these plates being effected by a slide, C, having inclined ribs working in inclined grooves in the lower surfaces of the plates B. The upper clamping-jaws are carried by arms h, attached to plates or blocks G, 35 hinged to blocks F, the latter blocks being attached to and sliding laterally with the plates B. The jaws H are forced down against the plates B by a cross-bar, K, connected by a link or pitman, J, with a crank, i, on a small shaft, I, having its bearings in the block F, said shaft being operated by a clamping arm or lever, L, attached thereto.

40 All of the parts above mentioned are, or may be, the same as in my Patent No. 319,700, hereinbefore referred to.

In this my improved clamp the spreading-lever D is pivoted by a pin, d', to a stationary block, a', attached to the base-plate A, said 45 lever being thus adapted to swing horizontally

and to move the spreading-slide C back and forth by means of the connecting-link d, loosely attached to said slide and lever. The clamping arm or lever L is provided with a projection, l, which is arranged in the path of movement of a projection, d', on the spreading-lever D as the latter lever is moved inward to bring the clamping-jaws together prior to releasing the work when a button-hole has been finished. This movement of the spreading-lever will 55 move the clamping-lever from the position shown by full lines to the position denoted by dotted lines in Fig. 5, and the shaft I, to which the clamping-lever is attached, will thus be turned far enough in the direction denoted by 60 the arrow in Fig. 7 to throw the crank i over the dead-center, and the arms h and clamping-jaws H will then be instantly lifted by springs h', placed between the block F and arms h, to the position indicated in Fig. 7, thereby fully 65 releasing the work. Thus it will be apparent that the work will be released by operating the spreading-lever only.

In clamping the work and spreading the button-hole the clamping-lever is first turned 75 to the position denoted by full lines in Fig. 5, and the spreading-lever is then moved to the position shown in Fig. 4.

In order that the clamping-jaws may hold the material securely without requiring too 80 much force in clamping, it has heretofore been customary to roughen their adjacent surfaces, to enable them to take a firm hold on the material; but this is objectionable when working on finely-finished leather and some other classes 85 of work, as the surface of the material is more or less marred by the roughened surfaces of the clamping-jaws. To obviate this difficulty and still enable the clamping-jaws to hold the work securely, so that it will not slip when 90 the button-hole is being spread, I have provided the lower clamping-jaws, B, with shallow concave grooves b, and the upper clamping-jaws, H, with convex projections h', fitting said grooves. These grooves and projections are 95 preferably slightly removed from the edges of the button-hole opening, so as to leave flat surfaces adjacent to said opening, the better to prevent the work from slipping when the button-hole is being spread.

It will be obvious that the construction above referred to may be reversed by forming the concave grooves in the upper jaws, if desired.

Having thus described my invention, I claim 5 and desire to secure by Letters Patent—

1. In a button-hole work-clamp, the combination, with the upper and lower laterally-movable clamping-jaws and a spreading-lever therefor, of an independently-movable clamp-10 ing arm or lever arranged to be engaged by the said spreading-lever as the latter is moved to bring the clamping-jaws toward each other, substantially as set forth.
2. In a button-hole clamp, the combination, 15 with the laterally-movable lower clamping-jaws or plates and a spreading-lever for operating the same, of a clamping arm or lever having a projection arranged to be engaged by the spreading-lever, and upper clamping-jaws 20 adapted to be raised to release the work when the said clamping arm or lever is operated by the said spreading-lever, substantially as set forth.
3. In a button-hole clamp, the combination, 25 with the laterally-movable upper and lower clamping-jaws and a spreading-lever for oper-

ating the same, of a shaft having a crank connected with the said upper clamping-jaws, said shaft being provided with a device adapted to be engaged by said spreading-lever to throw 30 the said crank past the dead-center, and springs for automatically lifting said upper clamping-jaws to release the work when the said crank is thus operated, substantially as set forth.

4. In a button-hole clamp, the combination, 35 with the laterally-movable upper and lower clamping-jaws and a spreading-lever for operating the same, of a shaft having a crank, a link and cross-bar for connecting said crank with the said upper jaws, a clamping arm or 40 lever having a projection adapted to be engaged by the spreading-lever, and springs for automatically lifting said upper jaws when the said crank is thrown past the dead-center by the impingement of the spreading-lever against 45 the clamping-lever, substantially as set forth.

In testimony whereof I affix my signature in presence of two witnesses.

JAMES G. GREENE.
